UNITED STATES PATENT OFFICE

92,053

DESIGN FOR AN EDUCATIONAL MODEL BUILDING

Henry E. Conklin, Roslyn, N. Y.

Application October 6, 1933, Serial No. 49,416

Term of patent 14 years

To all whom it may concern:

Be it known that I, HENRY E. CONKLIN, a citizen of the United States, residing at Roslyn, county of Nassau, and State of New York, have invented a new, original, and ornamental Design for an Educational Model Building, reference being had to the accompanying drawings forming part hereof,—

Fig. 1 is a view of the interior of one portion of the building;

Fig. 2 is a view of the interior of the other portion of the building; and

Fig. 3 is a diagrammatic top plan view of the entire model shown to a somewhat reduced scale.

The invention is clearly disclosed in the drawings from which it will be observed that Figs. 1 and 2 show separate parts of the complete article illustrated in Fig. 3.

I claim,—

The ornamental design for an educational model building as shown and described.

HENRY E. CONKLIN.
